UNITED STATES PATENT OFFICE

FINLEY MONROE, OF EMMETT, IDAHO

ELEVATOR

Application filed November 14, 1929. Serial No. 407,191.

This invention relates to the elevator forming the subject matter of U. S. Letters Patent No. 1,471,468, issued October 23, 1923. The elevator is adapted to be used for the purpose of elevating lumber and other materials being unloaded from railway cars and the like and arranged in piles and for the purpose of lowering piled lumber and other material being loaded on to railway cars and the like, and it is mounted upon and fixedly secured to a flat car so as to permit it to be moved to the place where the material is to be unloaded or loaded.

The present invention has for one of its objects to improve the elevator to the end that it may be mounted upon a flat car in a manner to permit it to be raised from the car and supported in its raised position above the track on which the car is mounted and at the place where a train of flat cars on the track is to be unloaded or loaded, whereby to permit the car supporting the elevator to be moved beyond the elevator so that the unloaded cars of the train may pass beneath the elevator during the unloading or loading of the train, and thus reduce to the minimum the time and labor necessary to effect the unloading or loading of the train.

To attain the foregoing and other objects, the nature of which will appear as the description proceeds, the invention comprehends the provision of the elevator with a base which shall be adapted to rest upon and firmly support the elevator from the car, and means carried by the base and adapted to be employed for the purpose of raising the elevator from the car and supporting it above the track.

The invention further comprehends the provision of means which shall be adapted to support the elevator firmly from the ends of the ties of the track and which shall be of such construction as to permit the car to be moved beyond the raised elevator and to permit unloaded cars to pass beneath the elevator while a train of such cars is being unloaded or loaded.

The invention consists in the construction, combination and arrangement of parts hereinafter fully described and claimed, and il-

lustrated in the accompanying drawings, wherein:—

Figure 1 is a view partly in side elevation and partly in vertical section of an elevator constructed in accordance with the present invention;

Figure 2 is a view partly in end elevation and partly in vertical section of the elevator, and

Figure 3 is a sectional view illustrating the manner in which the jack screws are connected with the base of the elevator and the nuts employed in connection with the jack screws.

Referring in detail to the drawings, 1 designates a flat car, and 2 designates the rails and 3 the ties of a track for the car. An elevator which comprises a base 4 and a tower 5, is mounted upon the car 1 so as to permit it to be moved to the place where other flat cars on the track are to be unloaded or loaded.

The base 4 is of elongated rectangular formation in plan, rests upon the car 1, and is preferably made of channel bars. The longitudinal bars 6 of the base 4 extend from one end of the car 1 to the other end thereof, and the transverse bars 7 of the base are arranged slightly beyond the ends of the car and extend beyond the sides thereof. The base 4 is provided at each end thereof with a pair of the bars 7, and the bars of each pair are secured together in relatively spaced relation by straps 8. The innermost of the bars 7 contact with the ends of the bars 6. The bars 6 and 7 are secured together by angle irons 9 which are secured to the bars 6, as at 10, and which pass through the bars 7 and are secured thereto, as at 11. The base 4 also comprises transverse bars 12, which are arranged in pairs above and parallel to the bars 7. The bars 12 are secured to and supported from the bars 7 by brackets 13 which also function to maintain the bars 7 at each end of the base 4 in relatively spaced relation. The bars 12 extend beyond the bars 7 at one side of the base 4 to provide supporting elements 12^a for a table 14.

The tower 5, which is similar to the corresponding part of the elevator disclosed in said prior patent, comprises standards 15

which are arranged at one side of the base 4 and are secured at their lower end, as at 16, to the bars 6. Braces 17 extend from the upper ends of the standards 15 to the other side 5 of the base 4, and are connected intermediate their ends to the standards by bars 18. A horizontal brace 19 and cross braces 20 are secured to and between the standards 15. Endless sprocket chains 21 extend longitudinally of the standards 15, and pass about 10 drive sprockets 22 journaled in the lower ends of the standards and supporting sprockets 23 journaled on the upper ends of the standards. Idle sprockets 24 which are 15 journaled in the standards 15 near the lower ends thereof, engage the inner runs of the sprocket chains 21.

Carriers 25 are secured to and extend right angularly from the sprocket chains 21. The 20 carriers 25, during the movement of the sprocket chains 21, pass upwardly or downwardly through the slots 26 formed in and extending transversely of the table 14. During the use of the elevator for the purpose 25 of stacking lumber being unloaded from cars, the carriers 25 pass upwardly through the table slots 26, and during the use of the elevator for the purpose of lowering lumber from the pile being loaded on to the cars, 30 the carriers pass downwardly through the table slots. During the unloading of the cars, the lumber is deposited upon the table 14, and is picked up therefrom by the carriers 25 and carried to the top of the pile 35 being formed. During the loading of the cars, the lumber is taken from the pile and deposited upon the carriers 25, the carriers deposit the lumber upon the table, and the lumber is picked up from the table and 40 placed upon the cars.

The sprocket chains 21 are similar to the sprocket chains disclosed in said prior patent, and the carriers 25 may embody the construction of either of the carriers disclosed in said 45 patent. The sprocket chains 21 are adapted to be driven from an engine 27 mounted upon the base 4. The engine 27 may be of any suitable type. A shaft 28 which carries the drive sprockets 22, may be driven from the 50 engine 27 by any suitable transmission mechanism, as suggested at 27^a, which will permit the sprocket chains 21 to be driven in a direction to pick up lumber from the table 14 or in a direction to deposit lumber 55 upon the table. These means may be similar to that shown in said prior patent.

The table 14 comprises a middle section 14^a which is arranged upon and fixed to the bars 12, and end sections 14^b which are pivotally 60 connected, as at 29, to the middle section. The table sections 14^b are adapted to be supported in alinement with the table section 14^a by props 30. The props 30 comprise yokes 30^a which are pivoted, as at 31, to the opposite sides of the free or outer ends of the

table sections 14^b. The props 30 also comprise rods 30^b which extend downwardly from the yokes 30^a and are adapted to engage the ground adjacent the track. The table sections 14^b are adapted to be supported in 70 an upright position with respect to the table section 14^a when the elevator is not in use. After the table sections 14^b have been swung into this position, the props 30 are swung 75 into an inwardly extended position with respect to the upper ends of the table sections, so as to permit the props to be engaged by hooks 32 which are connected as at 33, to the tower 5. The table sections 14^a and 14^b are provided with rollers 34 which permit lumber 80 to be shoved from either end of the table on to the middle section thereof.

The elevator is supported by the car 1 for movement along the track, and when it reaches the place where the cars are to be 85 unloaded or loaded, it is raised off of the car and supported in its raised position above the track. Means for raising the elevator and supporting it in its raised position, comprises foot bars 35 of angular formation and 90 equal in length to the corresponding dimension of the base 4. The foot bars 35 are arranged below the base 4 and outwardly of the rails 2, and they are connected to the base by jack screws 36. The jack screws 36 95 are slidably mounted between the bars 7 and 12 and pass through openings 8^a in the straps 8 which are secured to the lower sides of the bars 7. Brackets 37 extend downwardly from the bars 7 and have angular lower ends 37^a 100 through which the jack screws 36 pass. The straps 8 support the jack screws 36 near their upper ends and the bracket ends 37^a support the jack screws near their lower ends, with the result that the jack screws are connected 105 to the base 4 in a substantial manner and for vertical adjustment with respect thereto. The jack screws 36 are arranged at the junctions of the bars 6 and 7 and their lower ends 110 are turned inwardly, as at 36^a, to position the foot bars 35 above and close to the ends of the ties 3.

The jack screws 36 are adapted to be raised and lowered through the medium of nuts 38 which are engaged therewith and are arranged between and in contact with the bars 7 and 12. The bars 7 and 12 hold the nuts 38 against endwise movement, and the nuts are adapted to be turned through the medium of hand wheels 39 which extend centrally therefrom.

When the elevator reaches the place where the cars are to be unloaded or loaded, the nuts 38 are turned in a direction to move the foot bars 35 into contact with the ends of the ties 3, and thereafter they are turned in the same direction to raise the elevator off of the car 1. The elevator is now supported from the ties 3 and the car 1 is removed from beneath the elevator so as to permit the un- 130

loaded car to pass beneath the elevator during the unloading or loading operation. As the unloaded cars may pass beneath the elevator, the unloading or loading operation 5 may be performed in a comparatively short time, in a comparatively easy manner, and at the expenditure of comparatively little labor. After the cars have been unloaded or loaded, the car 1 is moved beneath the elevator and the elevator lowered on to the same by turning the nuts 38 in the reverse direction and thereafter, the nuts are turned in 10 the same direction to raise the foot bars 35 above the ties 3. The elevator may now be 15 moved along the track to another place where cars are to be unloaded or loaded. As the table sections 14^b are supported in upright position during the movement of the elevator from place to place along the track, they 20 cannot contact with a pile of lumber opposite a curve in the track. If desired, rods 40 may be employed for the purpose of preventing the tilting of the foot bars 35 during the raising of the elevator from the car 1 and during 25 the lowering of the elevator on to the car.

The bars 40 when employed are secured, as at 41, to the foot bars 35 and slidably mounted in openings 42 formed in the outermost base bar 6. The jack screws 36 support 30 the elevator from the foot bars 35 when the latter are in contact with the ties 3, and to prevent them from bending under the weight sustained by them, brace bars 43 are secured 35 to the outermost of the base bars 6 and to the brackets 37, the brackets also serving to prevent the bending of the jack screws.

While I have described the principle of 40 the invention, together with the structure which I now consider the preferred embodiment thereof, it is to be understood that the structure shown is merely illustrative and that such changes may be made, when desired, as fall within the scope of the invention 45 as claimed.

I claim:—

1. In combination, a flat car, an elevator having a base resting upon the car, straps secured to the base near the corners thereof 50 and provided with openings, brackets extending downwardly from the corners of the base and provided with inturned lower ends having openings alining with the openings in the straps, vertical jack screws slidably mounted in the openings of the straps and brackets, nuts rotatably mounted on the base and engaging the jack screws, foot bars secured to the lower ends of the jack screws, and braces secured to the base and brackets.
2. In combination, a flat car, an elevator 55 having a base resting upon the car and embodying end members each consisting of spaced lower and spaced upper bars, straps secured to the lower bars and provided with 60 openings connecting with the spaces between

the bars, brackets extending downwardly from the lower bars and having inturned lower ends registering with the opening in the straps, jack screws slidably passing through the brackets and straps and through 70 the spaces between the upper and lower bars, nuts engaging the jack screws and arranged between the lower and upper bars, the jack screws being provided with inturned lower ends, foot bars secured to the lower ends of the jack screws, and braces secured to the base and brackets.

In testimony whereof I hereunto affix my signature.
